UNITED STATES PATENT OFFICE

WILLIAM R. PETERSON, OF OSWEGO, NEW YORK, ASSIGNOR TO ST. REGIS PAPER COMPANY, OF NEW YORK, N. Y., A CORPORATION OF NEW YORK

CLOSING DEVICE FOR BAG FILLING MACHINES

Application filed November 5, 1930. Serial No. 493,519.

This invention relates to a closing device for a bag filling machine and more particularly for a machine adapted to fill valve bags.

The purpose of the invention is to provide an automatic cut-off of material fed to a valve bag when the weight of the bag reaches a predetermined amount. More particularly the object is to provide such a cut-off where the closing gate moves in a substantially horizontal direction, and to provide a simple and efficient construction for automatically tripping such a gate. Further objects and details of the invention will appear as the description proceeds.

In the accompanying drawings forming a part of this specification, Figure 1 is a side elevation of a gate and operating means embodying the invention, together with portions of a filling machine with which it is used; Fig. 2 is a front elevation of portions of two filling devices with the gate closing means of Fig. 1 attached thereto, the two devices being shown in different positions; Fig. 3 is a plan view of the parts shown in Fig. 2; Fig. 4 is a detail of a portion of a tripping device.

In the construction shown in the drawings, a frame 10 supports a hopper 11 from which material is fed through an outlet 12. This outlet is closed, when desired, by a gate 13.

In front of outlet 12 there is a filling tube 14 adapted to enter the valve of a bag. Tube 14 is mounted upon an A-shaped frame 15, the legs of which rest upon ends 16 of scale beams. A bag-carrying frame 17 is mounted upon the A-frame and may be moved by handle 18 from its full line position to its dotted line position in that figure, in order to discharge the bag after it has been filled.

Attached to the end of gate 13 there is a link 20 connected to the lower end 21 of a lever 22 fulcrumed on the frame at 23. A bracket 24 mounted on the frame has extending therefrom a pin 25 on which there is fulcrumed a tripping lever 26. Lever 26 has an end 27 in line with a screw 28 adjustable in a block 29 attached to A-frame 15. Block 29 also has a lug beneath end 27 of lever 26 and a screw 30 mounted in this lug adjusts the tension of a spring 31 bearing against the under side of end 27.

The other end of lever 26 carries a screw 32 adapted to contact a fixed lug 33 and limit the downward movement of that end of lever 26. This end also carries a wear block 34 with which there engages the end of a trip member 35. Trip member 35 is pivoted at 36 adjacent the path of lever 22 and carries an abutment plate 37. On lever 22 there is mounted a pawl 38, which is normally swung by a spring 39 until its end 40 engages the block 41 on lever 22 to which the pawl is pivoted.

Lever 22 carries an arm 42 between which and a fixed lug 43 there is a strong spring 44.

The operation of the device is as follows:

After a valve bag has been placed in position with its valve over filling tube 14, lever 22 is swung from the position in which it is shown at the right of Figs. 2 and 3 to the position in which it is shown at the left of those figures. It will be readily understood that gate 13 comprises a plate which stops the discharge while the plate is positioned to the right, as viewed in Figs. 2 and 3, while it has a perforation in line with outlet 12 when it is moved to the left, as viewed in Figs. 2 and 3. Therefore, the movement of lever 22 in the manner described, opens gate 13 and allows material to be discharged through tube 14 into the bag.

During this movement to the right of lever 22 spring 44 is compressed so that it constantly urges the lever and gate back towards closed position. However, during the movement of the lever, pawl 38 yields and passes abutment 37 on trip member 35, but immediately when the end of the pawl passes member 37, it is snapped back into the position in which it is shown in Fig. 4 so as to prevent return movement of the lever as long as trip member 35 is retained in the position in which it is shown in Figs. 1 and 4 and at the left of Figs. 2 and 3.

When beam 16 yields due to the weight of material fed into the bag, screw 28 depresses the outer end of lever 26, thereby raising block 34 out of the path of trip member 35, whereupon the expansion of spring 44 through pawl 38 forces trip member 35 to the position in which it is shown at the

right of Figs. 2 and 3, which allows the pawl to pass stop member 37 and, therefore, the lever is swung to gate closing position and the feed of material through the tube into the bag is thereby cut off. Thereafter the bag may be discharged by swinging cradle 17 to the position in which it is shown in dotted lines in Fig. 1. The apparatus is then ready to receive another bag and have the operation repeated.

It will be understood that trip 35 is automatically returned to its set position by any suitable means as soon as pawl 38 passes stop member 37, so that it will be in this position when the A-frame returns to its upper position and thereby lowers plate 34 in the path of trip 35. If for any reason trip 35 did not completely return to its set position before the upward movement of the A-frame, and plate 34 should encounter the end of the trip member, spring 31 will yield so that no damage is done and the opening movement of the gate controlling lever 22 is sufficient to complete the return of trip 35 to its set position.

One of the advantages of the disclosed construction is that lever 22 and link 20 move in the same plane as gate 13, so that there is no tendency to bend the gate and cramp it in its slideway. Another advantage lies in the position of the operating lever 22 at one side of the A-frame, so that it is accessible and does not interfere with any of the bag filling operations, and still is tripped by the movement of the A-frame with a minimum of working parts and with a minimum of force applied by the A-frame, so that the weighing operation is not disturbed by the tripping of the shut-off device.

It will be seen that a very simple and efficient means has been devised for automatically closing the gate when a bag has received a sufficient amount of material, and that this automatic tripping is accomplished with the minimum of interference with the weighing action.

While the construction shown in detail in the accompanying drawings has been found efficient and satisfactory, it will be readily understood that various changes may be made in the construction and arrangement of parts within the scope of the appended claims.

What I claim is:

1. In a valve bag filling machine, a discharge tube adapted to enter the valve of a bag, a frame adapted to support a bag in position to receive material from said tube, a vertically movable weighing member supporting said frame, a horizontally movable gate controlling admission of material into the tube, a lever, a link connecting one end of the lever to the gate, a spring normally urging the lever to gate-closing position, and a trip device normally holding the lever in

gate-opening position, and means connected with the frame for releasing the trip upon downward movement of the frame.

2. Apparatus in accordance with claim 1, and in which the lever is mounted for movement in the same plane as the gate.

3. Apparatus in accordance with claim 1 and in which said trip device comprises a tripping member movable in a plane perpendicular to the plane of movement of the lever.

4. Apparatus in accordance with claim 1 and in which the trip-releasing means comprises a lever mounted on a horizontal fulcrum and having one end in the path of a member on the frame and one end normally in the path of an end of the trip.

5. In a bag filling machine, a tube adapted to discharge material into a bag, a frame adapted to support a bag in position to receive material from said tube, a vertically movable weighing member supporting said frame, a gate controlling admission of material to said tube, a lever mounted for movement in the same plane as the gate and connected to the gate, means constantly urging the lever to gate-closing position, a trip for holding the lever in gate-opening position, said trip being pivoted to move in a plane perpendicular to the plane of movement of the lever and means for releasing the trip when the frame moves downward.

6. In a bag filling machine, a tube adapted to discharge material into a bag, a frame adapted to support a bag in position to receive material from said tube, a vertically movable weighing member supporting said frame, a horizontally movable gate controlling admission of material to said tube, a lever having a pawl thereon and mounted for movement in the plane of the gate and connected to the gate, means constantly urging the lever to gate-closing position, a trip for holding the lever in gate-opening position, said trip being pivoted for movement in a plane perpendicular to the plane of movement of the lever and having a short end and a long end, the short end being adapted to engage a pawl on the lever, a trigger mounted on a horizontal axis with one end normally in the path of the long end of said trip, and means on the frame engaging the other end of the trigger upon downward movement of the frame in response to the weight of a bag thereon.

In testimony whereof I have hereunto signed my name to this specification.

WILLIAM R. PETERSON.
